MACHINE FOR PROCESSING THERMO-PLASTIC HOSIERY

Harry S. Drum and William C. Dodson, Abington, Pa., assignors to Smith, Drum & Company, Philadelphia, Pa., a corporation of Pennsylvania

Application April 16, 1952, Serial No. 282,606

4 Claims. (Cl. 68—20)

1

The present invention relates to the processing of thermo-plastic hosiery and more particularly to a machine wherein stockings which have been preset on metal boards and are removed from the boards enter the machine to be treated, dyed and finished therein and leave the machine ready for inspection and packaging.

In the manufacture of hosiery of the synthetic type, as heretofore practiced, there are two methods in present day use, both of which require two or more handlings of the stockings and the use of skilled operators.

In one of these methods the knitted stockings are preset on boards individually and after presetting have to be pulled off of the boards by hand and bundled in dozen lots in a muslin wrapper and placed in a net bag. These bags are now placed in a dyeing machine where they are dyed and a finish applied. When this operation is completed they are removed from the dyeing machine and transferred to a mechanical extractor to remove excess liquid. After extracting, the operator removes the stockings by hand from the nets, takes off the muslin wrapping and pulls each stocking by hand onto a heated hosiery form for drying. In some hosiery plants the bundling and wrapping in muslin is dispensed with and the stockings dropped into the dye nets in loose form.

In another form, known as the "Dunn" system, the stockings as received from the knitting machine are hung in a conditioning chamber or cabinet where they are exposed to steam for the presetting operation. After removal from the cabinet, the stockings are then prepared for dyeing in either of the two ways of the first method, after which each stocking is reboarded, that is, pulled by hand onto an individual form for final finishing. Again after this finishing each stocking is pulled off of its board by hand.

Both of the foregoing methods have inherent disadvantages which manufacturers have tried to eliminate, without success, since the introduction of nylon and synthetic fibres. Primarily the trouble lies in the handling of the stockings during the process of manufacture, each such handling increasing the danger of damage to the stockings. Any abrasion of the skin of the operator's hands causes a snag or a pick in the stocking being handled, which then becomes a second, reducing production and increasing loss. In some hosiery mills seconds run as high as forty percent of a day's output. The chances of such damage are multiplied by boarding, netting and unnetting, reboarding, and final unboarding, all hand

2

operations. Also, even skilled operators vary the pulling effort on the stockings and the result is a variation in the length of the stocking. Furthermore, constant supervision is required to see that the net bags and forms are kept clean, and these must be cleaned on an average of once every two or three hours because any adhering compound will cause damage to the fabric and produce seconds.

10 Some of the objects of the present invention are: to provide a machine operating as a single unit for dyeing, finishing, and drying thermo-plastic hosiery as arranged one upon another in a flat stack, such hosiery having been previously 15 preset on metal form boards and removed from the boards for stacking and treating; to provide a hosiery-treating machine to operate upon a stack of preset stockings in a continuous succession of operations to result in finished stockings ready for 20 inspecting and packaging when the stack is removed from the machine; to provide a hosiery-treating machine which produces a finished stocking while eliminating the usual netting and unnetting of the stockings, the use of a separate 25 extractor, the hand reboarding for drying, and the final hand unboarding; to provide a machine for processing nylon and other synthetic stockings as a continuous operation without requiring metal forms or boards for drying and finishing, thus eliminating damage caused by the handling 30 and rehandling necessary with such boards; to provide a hosiery-treating machine wherein seconds or damaged stockings are reduced to a minimum; and to provide other objects and advantages as will hereinafter appear.

35 In the accompanying drawings, Fig. 1 represents a plan of a stocking-treating machine embodying one form of the present invention, with the cover removed; Fig. 2 represents a section on line 2—2 of Fig. 1; Fig. 3 represents a fragmentary vertical section on an enlarged scale showing one tray unit as mounted in the treating chamber; Fig. 4 represents an enlarged detail in plan showing the tray box guide and lift mechanism as associated with the machine casing; Fig. 45 5 represents a detail section on line 5—5 of Fig. 4 showing the guide and lift mechanism; and Fig. 6 represents a perspective partly broken away of a stocking-loaded tray.

50 Referring to the drawings, one form of the present invention comprises a casing 10, preferably generally rectangular in shape, which is open at the top and forms a treating chamber 11, access to which is had by the removal of a dome-shaped cover 12 which is normally sealed by

gaskets and clamped in place by suitable clamping bolts.

Rising from the bottom of the casing 10 and spaced from one end wall thereof is a partition 13, terminating in close proximity to the cover 12 to form an open top conduit 14 leading to the top of the chamber 11 and which at its lower end communicates with a pipe 15 through which the treating liquor and/or air is caused to circulate when the stockings are in place in the chamber 11.

Preferably the bottom 16 of the casing 10 is of a reversed dome shape having a centrally disposed opening 17 communicating with a fitting 18 from which the pipe 15 leads to the conduit 14. The lower end of the fitting 18 has an extension 20 for drain purposes controlled by a valve 21, and also provides an inlet 22 for introducing finishing compound and either hot or cold wash water as controlled by a valve 23.

For circulating treating liquor through the conduit 14 and chamber 11, an impeller unit 24 is located in the inlet to the pipe 15 with its driven shaft 25 extending exterior of the fitting 18 as a continuation of the shaft of the electric motor 26, which latter is preferably of the reversing type so that periodic change in the direction of flow of the treating liquor can take place when desired. The arrows in Fig. 2 indicate direct and reverse flow of liquor. Also, the bottom 16 is provided with an inlet pipe 27 controlled by a valve 28 to supply steam from a suitable source for heating the dye liquor.

For extracting excess liquor and drying the stockings after a dyeing operation, an inlet pipe 30 communicates with the pipe 15 for supplying air from a suitable source, which inlet pipe 30 is controlled by a valve 31. Also, a hand-operated disc valve 32 is located in the pipe 15 between the inlet pipe 30 and the impeller unit 24, which is to be opened when dye liquor is circulated, but closed when air is to be used for drying. In this latter case the drain valve 21 is open to drain the chamber 11 and discharge the air until the operation is completed.

In order to position the stockings for treatment, a plurality of open top trays 29 are provided, each, preferably, of rectangular shape having a meshed bottom screen 34. The tray side walls respectively have an inwardly disposed horizontal flange 35 at the bottom, and at the top a reversely bent horizontal flange 36, which terminate in an upwardly disposed vertical relatively short extension 37. The lower horizontally aligned pair of flanges 35 provide supports for the screen 34, which, as shown, is removable. The upper horizontally aligned pair of flanges 36 serve as supports for a superposed tray which is held against lateral displacement by the aforesaid retaining extensions 37. Thus, provision is made for vertically supporting a plurality of the trays, each of which carries a stack of horizontally disposed flat preset stockings. In the present instance the machine, as shown in Fig. 2, is adapted to handle four units side by side, each made up of twelve superposed trays, though the invention is not limited to the number of trays or units, except the height of a stack of trays should be limited in order to divide the treating chamber into upper and lower portions as continuations of the path of the circulating medium.

As a means for simultaneously handling each tray unit, a box 38 is provided which is open at the bottom except for inwardly disposed flanges 40, which provide seats for the lowermost of a

stack of trays, it being understood that the dimensions of the box 38 are such as to receive one of the stack units. Thus, each unit has its stack-holding box by which each stack of trays is placed in or removed from the treating chamber 11. Medially disposed on the outside of each end of each box is a channel-shaped member 41 welded vertically in place and arranged to be guided for vertical movement by channel guides 42 welded to the adjacent wall of the casing 10 in such spaced relation as will restrain the members 41 except for free vertical travel within the aforesaid guides 42. The upper end of each member 41 is connected to a swivelled link or bail 43, so that each aligned pair of such bails 43 can be simultaneously engaged by hooks on a suitable lifting apparatus of any well known type, for transferring a box with its stack of trays from one place to another.

20 As a means for supporting a box 38, or as in this instance, a plurality of such boxes, the casing 10 is provided with a transversely disposed horizontal false bottom 44 spaced from the true concave bottom 16, which spaced portion is an included part of the chamber 11, as will be understood. The false bottom 44 is provided with openings 45 respectively aligned with the tray units, so that the bottom 44 forms a seat for the box flanges 40, which thus surround the respective openings 45. Preferably, sealing gaskets 46 are interposed between the flanges 40 and the bottom 44, and also sealing gaskets 47 are located between the flanges 40 and the flanges 35.

To prevent collection of treating liquid in the spaces between the boxes and the casing, and also between the space between adjacent boxes, the false bottom 44 is provided with holes 48 aligned with these clearances for draining the aforesaid spaces.

45 Since the several trays have open tops, the mesh bottom 34 of each, in stacked relation, serves as the top and stack-retaining means for the tray below, except in the case of the topmost tray, where it is necessary to provide a separate screen 50 as the top and retaining means for the stack in the top tray.

For finally holding the trays in superposed position during the treating operation, a removable hold-down or clamping bar 51 is provided having projecting members 52 on the face to be juxtaposed to the top tray of the stack when the bar is in place across the top of the tray. These members 52 are located to register with the frame of the top screen 50 for clamping action of the bar 51, as the latter is drawn toward the trays by a nut 53 and bolt 54. Each bolt 54 has its head welded to the carrier member 41, while its threaded end traverses properly located apertures in the bar 51.

60 In operation, a stack of stocking-filled trays is placed in the handling box 38, and the latter then lowered into the treating chamber 11 to seat on the false bottom 44, whereupon the hold-down bar 51 is placed across the top tray and clamped in place to prevent improper shifting of the trays during treatment. With the drain valve 21 closed and the flap valve 32 open, the chamber 11 is supplied with the proper quantity of dye liquor, and the closure 12 locked in place. Steam can be admitted to the chamber 11 through pipe 27 by opening the valve 28 for heating the dye liquor. The motor 26 is now started to cause a continuous circulation of dye liquor through the pipe 15 to discharge above the stack of trays and be propelled downwardly through the stacked stockings.

When the dyeing is completed, the chamber is emptied by opening the drain valve 21, after which the valve 21 is closed and the valve 23 is opened to introduce finishing compound for circulation by the impeller 24 through the stacks of stockings for the required cycle of operation. The chamber 11 is now drained of the compound, which is replaced by wash water, either hot or cold, after which the extracting and drying cycles follow in succession. Having drawn off the wash water, the drain valve 21 remains open, the flap valve 32 is closed, and the valve 31 opened to admit air for extracting excess liquid from the stockings. This extracting air is circulated at relatively high velocity in order to create an effective extracting pressure by means of which all surface moisture is carried off. The stockings are now in condition for drying, and it is preferable to introduce heated air at a relatively low velocity to leave the stockings in dried finished condition, ready, upon removal from the treating chamber, for inspection and packaging. This removal is accomplished by mechanical lifting of each box of trays from the machine, as will be understood.

Having thus described our invention, we claim:

1. A machine for treating synthetic stockings which have been preset on boards, removed from the boards and arranged flat to form a stack of superposed stockings, comprising a casing and removable closure forming a closed chamber, a partition vertically disposed in said chamber forming a by-pass duct opening into the upper portion of said chamber, an apertured false bottom in said chamber mounted in spaced relation to the casing bottom, a plurality of trays arranged in superposed relation and supported by said false bottom, each tray having a pervious bottom supporting a stack of preset stockings, a fitting forming an outlet from the bottom of said chamber, a pipe connecting said fitting with said duct to form with said chamber a path for a

treating medium, and means for successively circulating dye liquor, liquid finishing compound and air in said path, whereby said stockings are dyed, finished, extracted and dried ready for inspection and packaging.

2. A machine for treating synthetic stockings in accordance with claim 1, wherein valve means selects a different circulating path for air than for the liquid medium.

10 3. A machine for treating synthetic stockings which have been preset on boards, removed from the boards, and arranged flat in superposed relation to form a stack, comprising a casing having a concave bottom provided with an outlet, a removable dome top for said casing, a partition vertically disposed in said casing and forming a duct for treating mediums, a tubular fitting leading from said outlet, a pipe forming a communication between said fitting and said duct, a motor-driven impeller for circulating liquid through said duct and chamber, a drain valve for said fitting, a stack of stocking-loaded trays having pervious bottoms respectively, and means for mounting said stack in said chamber in the path of said circulation.

20 4. A machine in accordance with claim 3, wherein a valve-controlled inlet for air under pressure communicates with said duct, and a flap valve is located between said inlet and the fitting.

HARRY S. DRUM.

WILLIAM C. DODSON.
